UNITED STATES PATENT OFFICE

103,434

DESIGN FOR AN INSECT POISON CONTAINER

John B. Rosefield, Oakland, Calif.

Application December 14, 1936, Serial No. 66,519

Term of patent 14 years

To all whom it may concern:

Be it known that I, John B. Rosefield, a citizen of the United States, residing at Oakland, in the county of Alameda, State of California, have invented a certain new, original, and ornamental Design for an Insect Poison Container, of which the following is a specification, reference being had to the accompanying drawing.

Figure 1 is a front elevation of an insect poison container showing my design.

Figure 2 is a side elevation of the same.

Figure 3 is a top plan view, and

Figure 4 is a bottom plan view.

I claim:

The ornamental design for an insect poison container, as shown.

JOHN B. ROSEFIELD.
